CLAIM

We claim the ornamental design for a bar pan, as shown and described.

DESCRIPTION

FIG. 1 is a top frontal perspective view of a first embodiment of a bar pan according to our new design;

FIG. 2 is a front view of the bar pan shown in FIG. 1;

FIG. 3 is a rear view of the bar pan shown in FIG. 1;

FIG. 4 is a left side view of the bar pan shown in FIG. 1;

FIG. 5 is a right side view of the bar pan shown in FIG. 1;

FIG. 6 is a top view of the bar pan shown in FIG. 1; and,

FIG. 7 is a bottom view of the bar pan shown in FIG. 1.

The views not shown form no part of the claimed design.

The broken lines in the drawings are for illustrative purposes only and form no part of the claimed design.
